COMPENSATED DIODE DETECTOR

Alfred W. Barber, Flushing, N. Y.

Application April 9, 1937, Serial No. 135,928

20 Claims. (Cl. 250—20)

My present invention relates to carrier wave receivers. More particularly it relates to a form of rectifier suitable for use in radio receivers and the like.

5 One object of my present invention is to provide circuits for generating automatic volume control and modulation frequency voltages in a radio or other carrier wave receiver. Another object is to eliminate the modulation frequency 10 output coupling condenser and the effects of the automatic volume control filter on the action of the detector in such a receiver. A particular object is to eliminate the distortion which may be generated in such circuits employing diode 15 detectors.

The most commonly used detector in radio receivers consists in a thermionic vacuum tube diode having a high resistance load. The demodulation voltages generated in this load, provided 20 it is by-passed by a condenser having a reactance approximately equal to or greater than the load resistance at modulation frequencies, consist in a direct current component proportional to the average amplitude of the impressed carrier voltage and a modulation frequency component proportional to the modulation of the carrier. It is usual to filter the direct current component by 25 means of a series resistor and a condenser to ground for application to the grid returns of amplifier tubes preceding the detector for purposes of automatic volume control. The modulation frequency component is selected by a series condenser and a high resistance to ground. At least 30 a part of the modulation frequency drop across this latter resistor is applied to the grid of a modulation frequency amplifier tube. I have 35 found that both the automatic volume control voltage filter and the modulation frequency coupling condenser cause distortions of the modulation frequency voltage generated by the system. 40 Both the automatic volume control filter condenser and the modulation frequency coupling condenser charge up to the average of one half 45 of the input carrier wave modulation peak envelope. Whenever the modulation envelope drops below this average these condensers feed-back thru the diode load resistor. When the modulation envelope drops below the feed-back drop across the diode load resistor, the diode is 50 cut-off and the modulation envelope and hence the modulation voltage is cut-off at this point. If the automatic volume control resistor and the modulation frequency coupling resistor in parallel are equal to a resistance R_0 and the diode load 55 resistance is R the modulation is cut-off at a

modulation percentage equal to $100R_0/R_0+R$ by this feed-back effect.

I have found that by separating the generation of automatic volume control and modulation frequency voltages, by by-passing the automatic volume control generating load resistor by a large condenser and by eliminating the modulation frequency coupling condenser that these distortions are eliminated. In my Patent Number 2,129,726 entitled "Rectifier circuits", granted September 10 1938, and filed on January 30, 1936, I have shown the basic circuit by which I accomplish this elimination of distortion. I have found, however, that certain improvements are possible over this basic circuit. I have found that an 15 unby-passed resistor in series with the automatic volume control voltage generating load reduces, and may be made to eliminate to any desired degree, distortion due to the loading of the detector 20 input circuit by the large capacity of this load circuit. In the basic system the automatic volume control voltage is subtracted from the voltage generated in the modulation frequency generating diode load producing a net modulation 25 frequency voltage which is applied conductively to the grid of the first modulation frequency amplifier tube. I have found it desirable in some cases to vary the amount of the opposing automatic volume control circuit drop as the modulation frequency output is varied so that the net 30 direct current bias applied to the following amplifier tube is at all times zero. The mode of operation of my improved system may be more easily and fully understood from the following description when taken in connection with the 35 drawing.

In the drawing,

Fig. 1 shows one mode of operation of my present invention.

Fig. 2 shows a modified form of my invention 40 embodying automatic volume control fixation for tuning purposes.

Fig. 3 shows still another modification of my invention.

In Fig. 1 I have shown one form of my improved detector circuit interposed between an amplifier C and an output device D. The amplifier C may be connected to an antenna A and ground B for the reception of radio signals or it 45 may be connected to a transmission line or other signal source circuit. The amplifier C may be a tuned radio frequency amplifier with one or more stages controlled by the automatic volume control voltage developed by the detector or it 50

45

50

55

may be taken to represent the portion of a super-heterodyne receiver up to the second detector in which case the automatic volume control voltage may be applied to one or more intermediate frequency amplifier stages, one or more radio frequency amplifier stages, the first detector or any suitable combination of the three. The output of amplifier C appears across a coil 1 which is inductively coupled to the detector input coil 2 which may be tuned to resonance by condenser 3. The output coil 1 will ordinarily be in the plate circuit of the final stage of the amplifier C and may or may not be tuned to resonance. Other means than the magnetic coupling may be used between the amplifier C and the detector as for instance capacity coupling and the detector input tuned circuit 2 and 3 may be replaced by other impedances such as a radio frequency choke or a resistance although I prefer the tuned circuit as shown.

The detector consists of two diodes and their associated circuits. One diode consisting of plate 4 and cathode 5 generates a steady voltage suitable for automatic volume control purposes by virtue of the high time constant load circuit consisting of resistor 6 and condenser 7 in parallel. The resistor 8 is connected in series between the diode cathode 5 and the high time constant load circuit 6 and 7. This resistor 8 should be large, of the order of 100,000 ohms, and its function is to prevent heavy loading of the input circuit on modulation peaks by the diode and the high time constant load. In operation condenser 7 charges up to approximately the average of the positive modulation envelope which is the same as one half the peak to peak value of the unmodulated radio or intermediate frequency input voltage. When the input voltage is modulated the modulation peaks rise above and fall below this condenser voltage. While the modulation envelope is above the voltage across condenser 7 the condenser charges thru the diode and resistance 8. Without resistor 8 this charging current is high and the input coil 2 is effectively shunted with a distortion producing load. Since the input voltage is also applied to the second diode which produces modulation frequency voltages it is important to preserve the input wave form undistorted. I have found that by limiting the charging current of condenser 7 by means of the series resistance 8 that this distortion of the input voltage may be reduced by any desired amount. If resistor 8 is made equal to the tuned impedance of the input circuit 2 and 3 or greater I have found that the input wave distortion is reduced to a negligible value.

If the cathode end of condenser 7 is grounded at G as shown, the other end of condenser 7 is negative with respect to ground and this negative voltage may be used for automatic volume control in the amplifier C by suitable connections well known in the art. A series filter may be used in the automatic volume control circuit consisting of a series resistor 9 and shunt condenser 10 to ground G for purposes of decoupling between the detector and the amplifier. If resistor 9 taken in conjunction with condenser 7 has a time constant of the order of 0.1 or more condenser 10 cannot feed-back any distorting voltage during inward modulation swings since it will take appreciable time for the current from condenser 10 to change the voltage across condenser 7 compared to the duration of the modulation peaks if the modulation is of audio frequencies. Evidently for other types of modulation the time constant

may be made such that feed-back is effectively prevented during modulation peaks. Thus the voltage across condenser 7 remains essentially constant at all times. When the modulation peaks are above the voltage across condenser 7 resistor 8 limits the charging current flowing into condenser 7 and when the modulation envelope is below the voltage drop across condenser 7 no current flows thru the diode. Thus the only distorting effect of the automatic volume control voltage generating load and diode is an alternation between no load for inward modulation swings and a load equal to resistor 8 for outward modulation swings. If resistor 8 is made large enough so that when it is shunted across the input circuit essentially no change takes place in the input voltage, the first diode and its load cannot distort the input voltage wave under any conditions of modulation.

The second diode comprising plate 11 and cathode 12 is connected in series with the modulation frequency load circuit consisting of resistor 13 and condenser 14 in parallel. Plate 11 is connected to the high end of the input coil 2 and the load circuit is connected between cathode 12 and a variable tap 18 on resistor 6. Condenser 14 should have a capacity C equal to $1/6.28 fR$ where f is the highest desired modulation frequency and R is the resistance of resistor 13. With this connection modulation frequency voltages and a direct current component appear across resistor 13. If a variable tap 15 is taken from resistor 13 and applied to the grid 16 of a modulation frequency amplifier tube 17, no coupling condenser is necessary between the diode and the amplifier tube grid. Taps 18 and 15 are mechanically coupled by arm 19 in such a manner that as tap 15 is moved toward cathode 12 tap 18 is moved toward the coil end of resistor 6 and as tap 15 is moved in the opposite direction toward the low end of resistor 13 tap 18 is moved toward the grounded end of resistor 6. If the taper of resistors 6 and 13 is such that the same percentage of the total resistance of resistor 6 is placed between tap 18 and ground as the percentage of resistor 13 placed between tap 15 and the low or return end of resistor 13, the direct current drops between ground G and grid 16 will essentially cancel each other leaving a net modulation frequency voltage between ground G and grid 16. Thus an essentially bias free modulation frequency voltage is applied to grid 16 and no blocking condenser is needed. This circuit therefore completely eliminates distortions due to the automatic volume control filter condenser and modulation frequency voltage blocking or coupling condenser experienced in conventional circuits.

Modulation frequency amplifier 17 may have a cathode 20 with a resistor 21 by-passed by condenser 22 connected from cathode 20 to ground G or other well known methods of bias may be used. The use of the automatic bias by means of the cathode series resistor has the advantage that any unbalance in direct current bias applied to the control grid is accommodated to some degree by a change in plate current and hence also a compensating change in cathode bias. Tube 17 may have a plate 23 feeding an output device D which may be additional amplifier stages, a loud speaker or other utilization means.

While not limited to these values I have found the following constants satisfactory to the operation of my invention in a radio sound broad-

cast receiver of the superheterodyne type having an intermediate frequency of 465 kilocycles:

Resistor 8 equal to 250,000 ohms
 5 Resistor 6 equal to 1 megohm
 Condenser 7 equal to 0.1 microfarad
 Resistor 9 equal to 1 megohm
 Condenser 10 equal to 0.1 microfarad
 Resistor 13 equal to 0.5 megohm
 10 Condenser 14 equal to 50 micro-microfarads
 Resistor 21 equal to 3000 ohms
 Condenser 22 equal to 25 microfarads

The circuit of Fig. 2 functions in a manner similar to that of Fig. 1 in so far as the components bearing similar numbers are concerned. The return of the modulation frequency load resistor 13 and condenser 14 is made to the coil end of the automatic volume control circuit so that when the output to grid 6 is reduced there is no reduction in the bias applied from the automatic volume control load circuit. The direct current bias on grid 6 thus increases as the output is reduced. This increase in bias, however, will be partially offset by the decrease in the drop across cathode 25 resistor 24 due to the reduced plate current which the increase in grid bias causes. A high time constant load consisting of condenser 26 shunted by resistor 25 may be placed in series with the modulation frequency load circuit. This high time constant circuit generates a bias which at low volume control settings will be substantially equal to the automatic volume control circuit bias and hence will cancel it. At high output settings of the volume control tap 15 this opposed bias will 35 be reduced in proportion to the direct current component generated in the modulation frequency load so that the net bias on grid 6 is at all times essentially zero. Switch 24 is provided to open the discharge path of condenser 7 thru resistor 6 thus preventing the automatic volume control circuit from discharging but permitting it to build up thru the diode and resistors 8 and 27 as described in the above mentioned patent for purposes of tuning to a signal. Resistor 27 40 functions much like resistor 8 in preventing loading of the input circuit. Placing condenser 14 on the tap on resistor 13 decreases the detection efficiency of the modulation diode on lowered volume control settings and aids in the changing of the drop across condenser 26 to match the output setting as described above.

The circuit of Fig. 3 functions similarly to that of Fig. 1 in so far as components bearing similar numbers are concerned. Condenser 7, however, discharges thru resistors 13 and 28 in series so that if they are equal the cathode end of resistor 28 has effectively one half the direct current component generated in resistor 13 cancelled. Similarly if resistor 28 is larger or smaller than resistor 13 more or less than half the direct current component cancellation takes place. Thus the drop across resistor 28 consists of the modulation frequency component across resistor 13 plus the direct current component across resistor 13 60 due to its rectification currents minus a portion of the direct current drop across condenser 7. Volume may be controlled by varying the tap 29 on resistor 28 and applying the drop from tap 29 to ground G to grid 6 of tube 17.

70 While I have shown and described only a few systems whereby my invention may be carried out, other forms are possible within the spirit and scope of the invention as set forth in the appended claims.

75 What I claim is:

1. In a carrier wave receiver, the combination of two diodes, a common input circuit, a load circuit connected in series with said input circuit and with each of said diodes and a substantially capacity free resistance circuit connected between one of said diodes, its associated load circuit, and said input circuit. 5

2. In a carrier wave receiver, the combination of two diode rectifiers, a rectifier input circuit, a load circuit connected between one of said diodes and said input circuit, a second load circuit having an alternating current impedance low compared to the alternating current impedance of the first said load circuit and a substantially capacity free resistance circuit connected in series 15 connected between the other of said diodes and said input circuit.

3. In a carrier wave receiver, the combination of two diode rectifiers, an input circuit, a load circuit connected in series with each of said diodes 20 and said input circuit, and additional means comprising an impedance circuit having a value of the order of the impedance of said input circuit at carrier frequencies connected in series with one of said load circuits. 25

4. In a carrier wave receiver, the combination of two diode rectifiers, an input circuit, a load circuit comprising a resistance and condenser connected in parallel connected in series with each of said diodes and said input circuit, wherein one 30 of said condensers is large compared to the other and additional means comprising a substantially capacity free resistor circuit connected in series with the larger of said condensers its associated diode and said input circuit. 35

5. In a carrier wave receiver, the combination of two diode rectifiers, an input circuit, a load circuit comprising a condenser and resistor in parallel connected in series with each of said diodes and said input circuit wherein one of said 40 condensers is large compared to the other of said condensers and additional means comprising a substantially capacity free resistor circuit having a value of the order of the magnitude of the tuned impedance of said input circuit connected in series with the larger of said load condensers. 45

6. In a carrier wave receiver, the combination of two diodes, a diode input circuit, a load circuit comprising a resistance and condenser connected in parallel connected between each of said diodes and said input circuit, wherein one of said condensers is large compared to the other of said condensers, an amplifier tube comprising at least a plate, a control grid and a cathode, a conductive 50 connection between one of said load circuits and ground and a conductive connection between the other of said load circuits and said grid and a resistance connected in series with said ground-connected load circuit and its associated diode. 60

7. A circuit as set forth in claim 6 and including an amplifier preceding said input circuit and a conductive connection between the ungrounded end of said grounded load circuit and at least one volume control point in said preceding amplifier. 65

8. A circuit as set forth in claim 6 and including a carrier frequency amplifier preceding said input circuit and a series resistance connected between the ungrounded end of said grounded load circuit and at least one point in 70 said carrier frequency amplifier and a condenser connected between the amplifier end of the last said resistor and ground.

9. In a carrier wave receiver, the combination of two diode rectifiers, a carrier responsive diode 75

input circuit, a load circuit comprising a resistance and condenser in parallel connected in series with each of said diodes and said input circuit, wherein one of said condensers is large compared to the other of said condensers, a resistor connected between said higher capacity diode circuit and its associated load, a conductive ground connection between the point common to said last resistor and said larger condenser, an amplifier tube including at least a plate, a control grid and a cathode, a variable tap point on each of said load resistors, a conductive connection between said grid and the tap on the resistor of the lower capacity load circuit, and a conductive connection between the end of said lower capacity load circuit remote from its associated diode and the other of said resistor taps.

10. A system as set forth in claim 9 wherein said taps are mechanically coupled.

20. 11. In a carrier wave receiver, the combination of a carrier current amplifier, an amplifier output impedance, a second impedance coupled electrically to the first said impedance, two diode rectifiers each comprising at least a cathode and a plate, a conductive connection between each of said diode plates and one end of said second impedance, a resistor connected between the cathode of the first of said diodes and ground, a first variably tapped resistor connected between ground and the other end of said second impedance, a second variably tapped resistor connected between the cathode of the second of said diodes and the tap point of said first tapped resistor, a condenser connected across said second 35 tapped resistor, a condenser large compared to the last said condenser connected across the first said tapped resistor, a conductive connection between one end of said larger condenser and at least one point in said carrier current amplifier, an amplifier tube including at least a plate, a control grid and a cathode, a condenser bypassed resistor connected between said cathode of said amplifier tube and ground and a conductive connection between said grid and the tap point of said second tapped resistor.

45. 12. In a carrier wave receiver, the combination of a carrier frequency amplifier, a double diode rectifier, a diode input circuit and a modulation frequency amplifier wherein the first section of said diode feeds a modulation frequency load circuit serially connected with said input circuit and said diode, means for conductively connecting said load circuit to said modulation frequency amplifier and wherein the second section of said diode feeds a second load circuit having a low 50 impedance to modulation frequencies serially connected with said input circuit and said second diode section, automatic volume control connections between said second load circuit and said carrier amplifier and including a high resistance in series with said second diode section and said input circuit.

60. 13. In a carrier current receiver, the combination of a carrier current amplifier, two diode rectifiers, a coupling impedance connected between said rectifiers and said amplifier, independent load circuits connected between each of said diodes and said coupling impedance, wherein one of said load circuits comprises a high impedance 65 to modulation frequencies in series with a low impedance to modulation frequencies, and the other of said low circuits comprises a resistor in series with a condenser and resistor in parallel, and means for opening the circuit of the last said 70 resistor.

75. 14. In a carrier wave receiver, the combination of a carrier frequency amplifier, two diode rectifiers, a modulation frequency amplifier tube including at least a plate, a control grid and a cathode, means for coupling said carrier frequency amplifier to said rectifiers including a rectifier input impedance, wherein said diodes each comprise at least a plate and a cathode, conductive connections between each of said diode plates and one end of said input impedance, a circuit connected between the cathode of the first of said diodes and the other end of said input impedance comprising a high resistance in series with a condenser and resistance in series connected in parallel with a resistance and switch in series, a conductive ground connection to the connection between said high resistance and said condenser, a resistance connected between the cathode end of said input impedance and at least one point in said carrier frequency amplifier, a condenser connected between at least one of the last said points and ground, a circuit connected between the cathode of the second of said diodes and the cathode end of said input impedance comprising a potentiometer in series with a condenser and resistor in parallel, a conductive connection between the tap of said potentiometer and said control grid, a condenser connected between said control grid and the second diode series condenser, a resistor and condenser in parallel connected between the cathode of said modulation frequency amplifier and ground and a connection between the plate of said modulation frequency amplifier and an output device.

80. 15. In a carrier frequency receiver, the combination of a carrier frequency amplifier, two diode rectifiers, a modulation frequency amplifier tube including at least a plate, a control grid and a cathode, means for coupling said carrier frequency amplifier to said rectifiers including a rectifier input impedance, wherein said diodes each comprise at least a plate and a cathode, conductive connections between each of said diode plates and one end of said input impedance, a circuit connected between the cathode of the first of said diodes and the other end of said input impedance comprising a resistor and condenser in series, a conductive connection between the point common to said resistor and condenser and ground, a circuit connected between the cathode end of said input impedance and at least one point in said carrier frequency amplifier comprising a series resistor, a condenser connected between at least one of said points in said carrier frequency amplifier and ground, a circuit connected between the cathode of the second of said diodes and the cathode end of said input impedance comprising a resistor and condenser in parallel, a potentiometer connected between the cathode of said second diode and ground, a conductive connection between the tap on said potentiometer and said control grid, a resistor and condenser in parallel connected between the cathode of said modulation frequency amplifier tube and ground and a connection between the plate of said modulation frequency amplifier tube and an output device.

85. 16. In a carrier wave receiver, the combination of a carrier frequency amplifier, two rectifiers, an impedance coupling said amplifier with said rectifiers, independent condensers connected in series with each of said rectifiers and said impedance, wherein one of said condensers is much larger than the other, means for limiting the carrier frequency charging current of the larger of said con- 90

densers, and utilization means conductively connected to one end of the smaller of said condensers.

17. A carrier wave rectifying system comprising, two rectifiers, a rectifier input circuit, means for charging independent condensers connected in series with said input circuit and each of said rectifiers, wherein one of said condensers is large compared to the other of said condensers and means for limiting the instantaneous charging current of the larger of said condensers.

18. A system as set forth in claim 17 wherein said current limiting means comprises a substantially capacity free resistor having a value greater than the magnitude of the impedance of said input circuit to unrectified currents.

19. In a carrier wave receiver, the combination of, a diode rectifier, a source of carrier signals to be rectified, a resistor and a condenser all connected in a series circuit, wherein at least a portion of said series circuit is completed by said resistor substantially free of shunting capacity.

20. In a carrier wave receiver, the combination of, a diode rectifier, a source of carrier frequency signals to be rectified, a carrier frequency impedance and a condenser all connected in a series circuit, wherein at least a portion of said series circuit is completed by said impedance substantially free of any carrier frequency low impedance shunting path.

ALFRED W. BARBER. 15
